UNITED STATES PATENT OFFICE

WILLARD G. COOK, OF WILKINSBURG, PENNSYLVANIA, ASSIGNOR TO WESTINGHOUSE ELECTRIC & MANUFACTURING COMPANY, A CORPORATION OF PENNSYLVANIA

CRANE HOIST CONTROL

Application filed May 20, 1930. Serial No. 453,928.

My invention relates to motor-control systems and particularly to such control systems as are employed in connection with the driving motors for cranes, hoists, and similar devices.

The object of my invention is to provide for cooperating manual and automatic time-limit speed control for a motor under all conditions of load and for accomplishing the desired result smoothly and without imposing abnormal strains on the motor or other parts of the system.

Other objects of my invention are to provide for inductive time-limit acceleration of the motor during starting, regardless of the load on the motor, and for dynamically braking the motor during stopping by a gradual, though comparatively rapid, change in the field current and a final stopping of the armature by connection through a low-resistance dynamic-braking circuit.

On lowering a crane carrying a heavy load, the operator may rapidly move the handle of the master switch from the "full-speed" hoisting position to the "off" position or, possibly, to the "lowering" position. In the control systems available at present an improper operation of the master switch may cause the dropping of the load in some instances and, in others, may cause a very strong dynamic-braking operation which subjects the hoisting machinery to abnormal stresses.

According to my invention, a control system is provided with a series motor which is controlled by a master switch in such manner that, in one direction of rotation, when the load is to be hoisted, the motor is started very slowly by reason of the inclusion of an armature shunt and a starting resistor in the motor circuit. The speed is readily controlled by opening the circuit of the armature shunt and by successively shunting portions or sections of the starting resistor.

When it is desired to reverse the motor, as in lowering a load that is not overhauling, the armature connections are reversed, and the field winding is connected in shunt relation to the armature. The accelerating resistor may be connected in series with the

field winding. A dynamic-braking resistor is connected in series with the armature circuit to limit the initial rush of current. A comparatively heavy current traverses the shunt field winding, since the starting resistor is short-circuited, thus raising the brake-shoe of the hoist brake and providing ample field strength to start the motor in the lowering direction. The lowering speed may be controlled through the master switch or by means of the automatic control relays, depending on the speed with which the controller is moved in the lowering direction.

In bringing the load to rest, the operator may, with the present system, return the controller to the "off" position or any one of the "hoist" positions and rely on the automatic means provided to gradually shunt the resistor from the field circuit to procure graduated dynamic braking prior to establishing the final dynamic-braking circuit for stopping and holding the motor. The motor speed is, therefore, first reduced by increased field excitation before final dynamic braking can be applied.

The novel features that I consider characteristic of my invention are set forth with particularity in the appended claims. The invention itself, however, both as to its organization and its method of operation, together with additional objects and advantages thereof, will best be understood from the following description of a specific embodiment, when read in connection with the accompanying drawings, in which:

Fig. 1 is a diagrammatic view showing the circuits and apparatus, embodying my invention, in operative relation;

Fig. 2 is a sequence chart indicating the order of operation of the several contactors;

Figs. 3, 4 and 5 are circuit diagrams showing the successive dynamic braking circuits that are established during the stopping operation of the lowering of an overhauling load; and

Fig. 6 shows the final low resistance dynamic braking circuit for stopping of the hoisting as well as the lowering operation.

Referring more particularly to the drawings, wherein the same reference characters

designate corresponding elements, 1 and 2 designate positive and negative conductors respectively leading from a suitable source of power not shown. A motor 190 is disposed 5 to be connected to the source of power through the agency of a plurality of line contactors 71, 145, 167, and 88. The line contactor 88 is disposed intermediate the negative line conductor 2 and the starting resistor 10 sections, while the other line contactors are disposed adjacent the positive line conductor 1. Actuation of line contactor 88 and 71 operates to connect the motor to the power lines as a series motor, whereas actuation of line contactor 88 and one or both of the line contactors 145 and 167 operates to connect the motor to the power lines as a shunt motor.

To provide for the appropriate acceleration of the motor, whether operating as a 20 series motor or as a shunt motor, the starting resistor sections are disposed to be shunted by accelerating contactors 110, 127, 133, and 136. A plurality of time-limit contactors 23, 41, 47, and 122 are provided to automatically control the time and sequence of operation of the accelerating contactors, thereby providing automatic time-controlled acceleration for the motor. The time-controlled acceleration for the motor becomes effective only when the controller 197 30 is operated too rapidly. By a slow movement of the controller 197, the motor 190 may be subjected to manual control, as will be pointed out more in detail hereinafter. For the present, it is sufficient to state that the time-limit contactors prevent abusing the motor or the control circuits, by careless, inadvertent or malicious manipulation of the controller and provide a definite maximum 35 rate of acceleration extending over a predetermined interval of time, regardless of the load on the motor. These facts will be more apparent after a study of Fig. 1, in connection with the following discussion.

40 A magnetic brake 191 is associated with the motor, and the actuation of the brake is controlled by the motor current. A plurality of control contactors 148, 94, 99, 153, 106, and 129 are also associated with the motor to control, among other operations, the establishment of a dynamic braking circuit for the motor when the voltage fails or the controller 197 is actuated to the "off" position or the motor is "plugged".

45 The position of the elements shown in Fig. 1 is the position they occupy when the conductors 1 and 2 are energized and the controller stands in the "off" position, and the various coils energized by the energization 50 of the conductors 1 and 2 have actuated their respective armatures. When the conductors 1 and 2 are energized a circuit is established from the positive conductor 1, through the conductors 3 and 4, actuating 55 coil 5 of contactor 153 and conductor 6 to

the negative line conductor 2. The contactor 153 is provided with two coils 5 and 104, but the coil 5 is so designed that it alone is not capable of operating the contactor. A second circuit is established from the positive line conductor 1, conductor 3, through conductor 8, controller segments 26, conductor 9, actuating coil 10 of contactor 23 to the negative conductor 2. A resistor 12 is disposed in parallel-circuit relation to the actuating coil 10.

70 The time-limit contactor 23 is also provided with a neutralizing coil 56, and, as shown, the armature having an associated contact-bridging member is biased to its contact-making position by a spring, the tension of which may be adjusted. By means of the adjustable spring and the resistor 12, the time constant of the time-limit contactor 23 may be accurately adjusted. The time-limit contactors 41, 47, and 122 are constructed like the time-limit contactor 23 except that, in connection with these contactors, no discharge resistors are required, since the magnetizing coils of the respective contactors are connected in parallel with sections of the starting resistor and thus discharge through these resistor sections.

75 Attention is called to the fact that the controller 197 appears to be provided with fifteen contact segments. Since the upper fourteen segments are all connected by heavy bars, there is, electrically, only one terminal segment and this terminal segment will hereinafter be referred to as controller segment 26.

80 Since the controller segment 26 is energized as above pointed out, a circuit is also established from contact finger 27 through conductor 14, actuating coil 16 of the accelerating contactor 110, conductor 17, contact fingers 18 and 20 bridged by the controller segment 19, and conductor 21 to the negative line 2. Connected in parallel circuit relation to the contactor 23 are the conductors 17 and 21 and contact fingers 18 and 20 bridged by the controller segment 19. Interruption of the contactor 23, therefore, does not interrupt the circuit for coil 16. A circuit is also established from the energized controller segment 26 through contact finger 38, through conductors 39 and 40, time-limit contactor 41, actuating coil 44 of the accelerating contactor 127, conductor 17, contact fingers 18 and 20—bridged by the controller segment 19—and conductor 21, to the conductor 2. Energizing circuits for the actuating coils 16 and 44 are also established through the contact finger 29 and conductors 30, 30' and contact members 35 to the conductor 40, and conductor 31 and contact members 32 to the conductor 14, respectively.

85 The neutralizing coils of the time-limit contactors are energized from conductor 1, through conductor 3, resistor sections 51 and 90

54, and neutralizing coils 52, 53, 55, and 56 to the negative conductor 2. The resistor 51 has a resistance value of about 2400 ohms, whereas the resistance value of the resistor 54 is only about 800 ohms. The actual resistance values used for these resistors may vary over a great range but the ratio variations of the resistance values are kept very small for a purpose discussed more in detail hereinafter.

10 A circuit for the actuating coil 50 of the accelerating contactor 133 is established from the energized controller segment 26 through contact finger 45, conductors 46 and 49, time-limit contactor 47, actuating coil 50, conductor 17, contact fingers 18 and 20—bridged by controller segment 19—and conductor 21 to the line conductor 2.

15 The circuits just discussed cause the energization of coils 10, 16, 44 and 50 and, as a consequence, contactor 23 opens, and accelerating contactors 110, 127 and 133 are closed. The control circuits are, therefore, so energized that the controller may be moved either 20 to a hoisting or to a lowering position. If the controller is moved to the first hoisting position, coils 16, 44 and 50 are deenergized, and contactors 110, 127 and 133 are opened, and other circuits are established.

25 Movement of the controller to the first hoist position causes operation of line contactors 71, and 88, and armature shunt contactor 94. The circuits for these contactors may be traced from the positive line conductor 1, through conductors 3 and 8, contact fingers 25 and 57—bridged by the controller segment 26—conductor 58, actuating coil 59 for the line contactor 71 and conductor 60 to the line 2. A parallel circuit to the coil 59 is also established from conductor 58 through actuating coil 62 and conductor 60 to the line 2. Another circuit extends from controller segment 26 through contact finger 63, conductor 64, actuating coil 65 of line contactor 88 to the line 2. Connected in parallel-circuit relation to coil 65 is operating coil 66 of contactor 99. A third circuit is established from controller segment 26 through contact finger 68, actuating coil 70 of the armature shunt contactor 94 and conductor 60 to the negative line 2.

30 Operation of the controller to the first hoist position also causes deenergization of all the energized operating coils of the accelerating contactors and, in consequence, the contacts of the accelerating contactors open, thus inserting all the sections of the starting resistor in the circuit of the motor. While the controller is still in the first hoist position and by reason of the circuits thus established, contactors 88, 71, 94 and 106 close and contact members 99 and 32 open.

35 A circuit for the motor is thus established from the positive line conductor, contactor 71, conductor 73, the armature of the motor

190, field magnet winding 76, actuating coil 78 of the hoist brake 191, conductor 79, the resistor sections 80, 81, 82, and 83 of the starting resistor 192, contactors 85 and 88 to the negative line 2. An armature shunt is 70 established which extends from conductor 73 through braking resistor 91, auxiliary resistor 93, contactor 94, conductor 96, auxiliary starting resistor sections 97 and 98 to the lower armature terminal. This armature shunt permits a very slow initial hoisting operation, so that chains and hooks may be adjusted before the load is actually being raised.

30 A circuit in parallel with the armature is also established from one armature terminal through conductor 73, conductor 101, coils 102 and 104 in parallel to the other armature terminal. In this instance, the coil 104 opposes coil 5, and the contactor 153 is not operated, whereas the coil 102 aids coil 62 and the contactor 106 is operated. The relative strength of coils 62 and 102 is such that coil 102 alone will cause operation of contactor 106 when the motor has attained a predetermined speed. This is important only in lowering when the load is non-overhauling, as will be made clearer hereinafter.

35 Since all the starting-resistor sections are connected in series with the motor, the motor starts at a slow speed and, at the same time, the coils of the time-limit relays 41, 47 and 122 are energized by circuits from conductor 113, magnetizing coil 114 of time-limit relay 122; conductor 118 through magnetizing coil 116 of time-limit relay 47; and conductor 119 through magnetizing coil 117 of the time-limit relay 41 to conductor 115, contactor 88 to the negative line conductor 2.

40 Energization of the time-limit relays causes contactors 41, 47, and 122 to open and contact members 170 to close. This operation and the closing of contactor 106 does not cause any immediate effect, since contact fingers 29, 38, and 45 are not in engagement with controller segment 26. The opening of the contactor 99 prevents the shunting of the starting-resistor sections, and the opening of contact members 32 permits the continuance of 45 the manual control of the energization of coil 44 when the controller is moved to the third position, for, in the third position, contact fingers 25 and 27 are again bridged by controller segments, as in the "off" position.

45 When the controller is moved to the second hoist position, coil 70 is deenergized to cause the opening of contactor 94. The opening of contactor 94 opens the armature shunt circuit from 91 to 98. The motor is thus connected as a series motor with all starting resistor sections 80 to 83, inclusive, in series with the armature. The resistor section 160, shunted by contactor 85, is not a portion of the starting resistor, and is shunted during 50

the hoisting operations. During the lowering operation, the resistor section 160 is in the circuit of the field magnet winding and causes high-speed lowering of the load.

- 5 Movement of the controller to the third hoist position interrupts the circuit through the contact fingers 25 and 28, thus deenergizing magnetizing coil 10 of time-limit relay 23. When contact fingers 25 and 27 are bridged by controller segment 26, nothing can happen until the time-limit relay 23 drops open after a predetermined interval of time, depending upon the setting and design of the time-limit relay. After the lapse of the required time, a circuit is established from the positive line conductor 1, through conductor 8, contact fingers 25 and 27, conductor 14, actuating coil 16 of accelerating contactor 110, conductor 17 and contactor 23 to the line conductor 2.
- 10 The operation of accelerating contactor 110 shunts resistor sections 83 and 160. The shunting of resistor section 83 causes the de-energization of time-limit relay 41, and this relay, after a predetermined interval of time, closes its contact members. The controller may now be moved to the fourth controller position.
- 15 Movement of the controller to the fourth position establishes a circuit from the positive line conductor 1, through conductor 8, contact fingers 25 and 38—bridged by segment 26—conductors 39 and 40, time-limit contactor 41, actuating coil 44 of accelerating contactor 127, contactor 23 to the conductor 2. A circuit is also established from conductor 39, contact members 35, conductors 30' and 105, contactor 106, coil 108 of contactor 129, conductor 17 and contactor 23 to the conductor 2. Whether contactor 129 operates by reason of the energization of coil 108 is immaterial at this stage of the operation, since no circuits are thereby established but the design is such that contactor 129 does not operate, or, if it does operate, it operates slowly.
- 20 The coil 44 is energized, and the contactor 127 stands closed; therefore, when the controller is actuated to its fourth position, resistor sections 82, 83 and 160 and magnetizing coils 116 and 117 are shunted. After a definite time interval, time-limit contactor 47 closes and the controller may be moved to the fifth hoist position.
- 25 When the controller stands in the fifth position, contact fingers 25 and 45 are bridged, and the accelerating contactor 133 closes to shunt another section of the starting resistor and to shunt the magnetizing coil 114 of the time-relay 122. After a definite time interval, relay 122 closes to energize the last accelerating contactor 136, and the controller may be moved to the sixth hoist position. Movement of the controller to the sixth hoist position causes the shunting of the last

starting resistor section 80, and the motor operates at full hoisting speed.

If the attendant desires to stop the hoisting operation, the controller is moved to the "off" position. By this operation, the line contactors 71 and 88 are deenergized, and the motor is disconnected from the source of power. The coil 66 is also deenergized, and the control relay 99 immediately closes its contacts. This relay is provided with a spring 198 which insures the establishment of a firm contact between the contact members of the relay 99. A low-resistance dynamic-braking circuit is established from one motor armature terminal, through field magnet winding 76, the contactor 99, resistor 91 to the other motor armature terminal, and the motor is stopped quickly.

When it is desired to move the hoist hook in the lowering direction, the controller 197 is moved to the first lowering position, thereby establishing a plurality of parallel circuits. One of the circuits may be traced from conductor 1 through conductor 8, contact fingers 25 and 138—bridged by segment 26—conductor 139, actuating coil 141 of line contactor 145, and conductor 143 to the conductor 2. The actuating coil 142 of the contactor 148 is connected in parallel-circuit relation to the actuating coil 141. Energization of coils 141 and 142 causes the closing of contactors 145 and 148, respectively. Another circuit may be traced from the energized conductor 8, through contact fingers 25 and 63—bridged by segment 26—conductor 64, actuating coil 65 of line contactor 88 to the conductor 2. The actuating coil 66 of contactor 99 is connected in parallel to the coil 65. Energization of coil 65 operates to close the line contactor 88 and the simultaneous energization of coil 66 causes opening of contactor 99. A further circuit is established from segment 26, through contact finger 120, conductor 121, time-limit contactor 122, actuating coil 125 of accelerating contactor 136 to the negatively energized conductor 17.

A circuit for the motor is now established from conductor 1 through contactor 145, auxiliary starting resistor sections 97 and 98, field magnet winding 76, operating coil 78 of the hoist brake 191, conductor 79, accelerating contactors 136, 133, 127 and 110, line contactor 88 to the conductor 2.

From the right hand junction of resistor section 98, a motor circuit is established through the motor armature, conductor 73, braking resistor 91, conductor 147, contactor 148, actuating coil 151 and line contactor 88 to conductor 2. It will be noted, by the circuits just traced, the motor is connected as a shunt-wound motor, and the resistor sections of the starting resistor are connected in series with the field winding and thus operate

70

75

105

110

115

120

125

130

merely as a variable rheostat for the field of a shunt-wound motor.

For the first controller position in the lowering direction, however, the starting-

- 5 resistor sections are short-circuited, and the initial field excitation is comparatively large so that the motor starts at a slow rate. Opening of contactor 99 prevents short-circuiting of the actuating coil 78 of the hoist brake 191. 10 The heavy current thus traversing the field winding and the actuating coil 78 insures that the hoist brake is raised and that the motor starts. Since the resistor sections in series with the field winding are shunted, the 15 voltage drop across coil 151 does not cause operation of relay 129. Attention is also called to the fact, for the first lowering position, the shunts for the starting resistor sections were established by the energization 20 of coils 16, 44, 50, and 125 by circuits extending from the energized contact fingers 27, 29, 38, 45, and 120, respectively, and the contact fingers 18 and 20 bridged by controller segment 19. Portions of the control circuit 25 are maintained throughout the lowering positions by reason of the fact that contact fingers 18 and 20 are always bridged during the lowering operation.

Because of the fact that the starting resistor is shunted during initial stages of the lowering operation, none of the time-limit relays 41, 47 or 122 have operated to open circuit position. By completion of the motor circuit, control contactor 153 is caused to 30 operate by reason of the circuit established from the one armature terminal, coils 102 and 104 connected in parallel and conductors 101 and 73 to the other armature terminal. Energization of coil 104 operates the contactor 153, whereas energization of coil 102, acting in opposition to coil 62, has no effect on contactor 106.

Since it is very desirable that the lowering speed be as high as possible when the load is not overhauling, means are provided for changing the time constant of the time-limit relays during the lowering operation. Closing of control contactor 153 establishes a circuit from the energized segment 26 45 through contact finger 29, conductor 30, contactor 153, resistor 54, neutralizing coils 52, 53, 55, and 56 of the time-limit relays 122, 47, 41, and 23, respectively. The relative resistance values of resistors 51 and 54 is about 50 three to one, or, if desirable, may be as high as two to one. The resistor 51 is shunted by the circuit just traced, and such shunting increases the demagnetizing effect of the coils 52, 53, 55, and 56, so that these time-limit 55 relays, after having been energized, operate much more rapidly than during the hoisting operation. As was previously suggested, the resistance value of the resistor 51, for this particular application, may be somewhere 60 near 2400 ohms, whereas the resistance value

of resistor 54 may be somewhere near 800 ohms. However, I do not wish to limit myself to any particular resistance value herein mentioned.

Movement of the controller to the second 70 lowering position causes the deenergization of coil 125 and the consequent insertion of resistor section 80 in series with the field winding, thereby causing acceleration of the motor in the lowering direction.

The movement of the controller to the third lowering position causes deenergization of the coil 50 of the accelerating contactor 133 with the consequent insertion of resistor section 81 in the field circuit. Insertion 80 of the resistor section 81 causes energization of magnetizing coil 114 and thus the opening of contactor 122. When the controller is moved to the fourth position, coil 44 of accelerating contactor 127 is deenergized and resistor 82 is inserted in the field circuit. By this operation, magnetizing coil 116 of time-limit relay or contactor 47 is 85 energized and the contactor opens.

Movement of the controller to the fifth 90 lowering position causes the interruption of the circuit through contact fingers 25 and 27; however, this operation does not, of itself, interrupt the circuit for the actuating coil 16 of the accelerating contactor 110 because a circuit still exists to this coil from the positively energized conductor 8, through contact fingers 25 and 29—bridged by segment 26—conductors 30 and 31, contact members 32, conductor 14, coil 16, contactor 23, 95 or through segment 19 to conductor 2. After the motor has reached a predetermined speed, the control contactor 106 will operate to open contact members 32, thereby deenergizing the coil 16, whereupon the resistor section 83 is 100 placed in series with the field winding 76. By this latter operation, magnetizing coil 117 is energized and, in consequence, contactor 41 is opened. Attention is called to the 105 fact that contactor 85 is still closed, so that the resistor section 160 is still shunted. However, with the insertion of resistor sections 80 to 83, inclusive, the IR-drop across actuating coil 151 is sufficient to cause control contactor 129 to close; however, closure of 110 contactor 129 does not establish actuating circuits for control contactors 85 and 167.

Movement of the controller to the sixth 115 lowering position causes the bridging of contact fingers 25 and 131 by segment 26, and the establishment of a circuit from contact finger 131, conductor 161, control contactor 129, conductor 162, actuating coil 164, conductor 163 to conductor 2. The actuating coil 163 for the auxiliary line contactor 167 is connected in parallel to coil 164. Energization of these circuits causes the shunting of resistor section 97 of the auxiliary starting resistor and the shunting of resistor 160 120 connected in series with the field winding 125

76. In consequence, a very high-speed lowering of the hook is provided.

All of the circuits just traced, and the sequence of operation for the lowering direction take place only when the load is non-overhauling, and it is desired to drive the hook down very rapidly. When the load is overhauling, the motor, being driven by the overhauling load, operates as a series generator and prevents excessive lowering speeds for the load. If it is desired to stop the lowering operation, the controller may be moved to the "off" position, or any one of the hoist positions, and the motor will be stopped by reason of the establishment of a dynamic-braking circuit through the armature and the starting resistor sections. Assuming that the controller is moved to the "off" position, circuits are established for the time-limit relay 23, actuating coil 16 of accelerating contactor 110, and since contact members 170 are closed by the previous energization of time-limit contactor 47, circuits are also established for the actuating coils 172 and 173 of control contactors 148 and 99, respectively. The energization of coil 172 merely aids the action of coil 142, since this control relay 148 is already in closed position, and energization of coil 173 insures that, for the time being, contactor 99 remains open. The dynamic-braking circuit established for the motor may be traced from the armature, through conductor 73, braking resistor 91, conductor 147, contactor 148, actuating coil 151 of control contactor 129, conductor 115, contactor 85, resistor sections 83, 82, 81, and 80, conductor 79, brake-operating coil 78, field winding 76 to the other armature terminal. Fig. 3 illustrates this dynamic-braking circuit. Coils 102 and 104 are also energized during dynamic braking. Energization of coil 104 insures that contactor 153 remains closed to connect resistor 54, having only about one third the resistance value of resistor 51, in circuit relation with the neutralizing coils 52, 53, 55, and 56. The time constants of the time-limit relays are, therefore, of a relatively lower value during dynamic braking.

50. Since magnetizing coil 10 is energized, the time-limit contactor 23 is open and the control circuit is maintained only through the contact fingers 18 and 20, segment 19 and conductors 17 and 21.

55. Since all of the magnetizing coils 10, 117, 116, and 114 are energized, the time-limit contactors 23, 41, 47, and 122 stand open, but movement of the controller to the "off" position causes energization of coil 16 of the accelerating contactor 110. In consequence, magnetizing coil 117 is shunted by the operation of the contactor 110 to shunt resistor section 83. The time-limit relay or contactor 41, resistor 51 being shunted, closes after a 60 very short predetermined interval of time. 65 It should also be noted that the operation of

contactor 110 establishes the dynamic-braking circuit shown in Fig. 4.

Closing of the time-limit contactor 41 causes the energization of coil 44 of accelerating contactor 127 with the consequent shunting of resistor section 82 and the shunting of the magnetizing coil 116. This operation establishes the dynamic-braking circuit shown in Fig. 5. After a very short predetermined interval of time, time-limit relay 47 closes to thus effect the operation of accelerating contactor 133, which shunts resistor section 81 and magnetizing coil 114. Time-limit relay 122 in turn effects the shunting of resistor section 80. Two dynamic-braking circuits, similar to those shown in Figs. 4 and 5, having successively lower resistance values, may thus be established.

70. From the foregoing, it is apparent that the 75 resistance value of the dynamic-braking circuit gradually decreases and, since the field winding 76 is in series with the dynamic-braking circuit the excitation of the motor is correspondingly increased. The resistance value of the dynamic-braking circuit thus 80 varies in inverse order to the field excitation, thus providing a graduated dynamic-braking effect which starts at a low value and rises, in 85 a cumulative manner, to a very high value.

90. The dynamic-braking effect is, however, further increased, independent of the changes in field excitation, by the provision of a low-resistance dynamic-braking circuit. After 95 the operation of time-limit contact 47, contact members 170 are interrupted to cause de-energization of coils 172 and 173, with the consequent opening of contact 148 and the 100 closing of contactor 99.

105. The low-resistance dynamic-braking circuit is shown in Fig. 6, and may be traced from one terminal of the motor, through conductor 73, braking resistor 91, contactor 99, and field winding 76 to the other armature terminal. By reason of this low-resistance 110 dynamic-braking circuit and because of the fact that the hoist brake is also applied after the interruption of contactor 148, the motor is brought to rest almost immediately, and accurate positioning of the load is thus 115 accomplished. This last-stage low-resistance dynamic-braking circuit may be established any time after opening of contact members 170, but the preferable design is such that this last circuit is established immediately 120 after the closing of accelerating contactor 136.

125. When the motor is plugged from high-speed lowering, contact finger 28 is engaged long enough to cause energization of magnetizing coil 10 to operate contactor 23. The motor thus comes to rest by dynamic braking, and by the same sequence of dynamic-braking circuits heretofore explained in connection with a movement of the controller to the 130 "off" position. During reversal of the motor,

the accelerating contactors 110, 127, 133, and 136 have time to open, thus placing the starting resistor sections in the motor circuit. The time-limit contactors 23, 41, 47, and 122, since the voltage on their magnetizing coils passes through zero and then builds up in the opposite direction, do not operate, i. e., remain closed. During the transition, the contactor 23 is obviously open for a predetermined interval of time, and since contact fingers 18 and 20 are not bridged, the accelerating relays do not operate before the lapse of a predetermined interval of time, depending on the design and adjustment of time-limit contactor 23.

During movement of the controller to plugging position, the main coils 66 and 142 of control contactors 99 and 148, respectively, are deenergized, and when the time-limit relays operate successively to open their respective contact members and to close contact members 170, the control contactors 148 and 99 are not caused to operate, because coils 172 and 173 are comparatively weak, i. e., 25 are merely holding coils once the main coils 66 and 142 have caused the contactors to operate.

Assuming the controller is thrown to the sixth hoist position, contact fingers 63, 57, 38, 30 27, 45 and 120 are connected to the positive conductor 1. The motor stops by the dynamic-braking effect set up, and, after a predetermined interval of time, contactor 23 closes, coil 16 is energized and accelerating contactor 110 closes. This operation deenergizes coil 117 and, after a definite time, contactor 41 closes. The closure of this latter contactor effects energization of coil 44 and accelerating contactor 127 closes. By successive steps like these discussed, accelerating contactor 136 is eventually operated to shunt the last starting resistor section 80. The motor is now moving at full speed in the hoist direction. Obviously, these same steps 45 may be used to accelerate the motor from standstill to full hoisting speed by manual control as hereinbefore discussed.

By moving the controller to the "sixth" hoist position initially, the manual control of 50 acceleration is not used. From these considerations, it is apparent that the motor may not be forced to accelerate faster than a predetermined maximum rate, as determined by the design and adjustment of the several time-limit relays. The motor may, however, be accelerated at a slower rate than that for which the time-limit relays are set. The circuits and sequence of operation above discussed, when a slow movement of the controller in the 55 hoist direction was considered, show just such comparatively slow manual control.

It will be recognized that a dynamic-braking resistor of low ohmic value is desirable, inasmuch as braking is usually accomplished 60 from slow speed. However, an operator will

frequently attempt to stop a heavy lowering load more quickly than should be attempted, thereby causing the load and control system to handle excessive currents and produce destructive arcing of the motor commutator 70 and the control contactors. Undue mechanical stresses are also induced. In the present system, the equipment is automatically protected, as described, by the provision of a graduated dynamic-braking effect and by the provision of a control system wherein any false movement of the controller cannot injure the equipment. The manual and automatic control systems further protects the equipment by the provision of the same successive dynamic-braking circuits, regardless of whether a false movement of the controller is made or voltage on the system fails.

Although I have shown and described certain specific embodiments of my invention, I 85 am fully aware that many modifications thereof are possible. My invention therefore, is not to be restricted except insofar as is necessitated by the prior art and by the spirit of the appended claims.

I claim as my invention:

1. The combination with an electric motor having a field-magnet winding, a dynamic-braking circuit cooperating with said motor, for producing a dynamic-braking effect in the motor, means for gradually and proportionally decreasing the ohmic resistance in the dynamic-braking circuit and the field-magnet winding, respectively.

2. The combination with an electric motor having a field-magnet winding, a dynamic-braking circuit for connection to the motor and including the field-magnet winding, means for progressively varying the field excitation during dynamic-braking, a second dynamic-braking circuit having a resistance value lower than said first-named dynamic-braking circuit, and means for establishing the low-resistance dynamic-braking circuit for the motor during variations of the field excitation.

3. The combination with an electric motor having a field-magnet winding, a variable resistor, dynamic-braking circuits for connection in series with the field-magnet winding, the motor and the variable resistor, means for successively varying the resistance value of the resistor whereby the field excitation is gradually increased and whereby the dynamic-braking circuits are resolved into a plurality of successively established dynamic-braking circuits having progressively lower resistance values, and a dynamic-braking circuit, having a lower resistance value than the respective resistance values of the dynamic-braking circuits including the variable resistor for connection to the motor during the establishment of the plurality of dynamic-braking circuits.

4. The combination with an electric motor

- having a field winding, a resistor having a plurality of sections for connection in series with the field winding, dynamic-braking circuits including the resistor, the motor, and the field winding all connected in series circuit relation, time limit relays operable after the lapse of definite intervals of time for successively effecting the shunting of sections of the resistor, and a dynamic-braking circuit, having a resistance value lower than any one of said dynamic braking circuits, for connection to the motor during shunting of the said resistor sections.
5. The combination with an electric motor having a field-magnet winding, a starting resistor, dynamic-braking circuits for connection to the motor and including the starting resistor, and time-limit relays for effecting the shunting of the starting resistor sections at a predetermined rate during starting of the motor means for changing the characteristics of the time-limit relays for short-circuiting the starting-resistor sections at a more rapid predetermined rate during dynamic-braking.
6. The combination with an electric motor having field windings and dynamic-braking circuits the resistance value of which may be varied, means for simultaneously and proportionally increasing the field excitation of the motor and decreasing the resistance value of the dynamic-braking circuits over a predetermined range during a predetermined interval of time.
- 35 7. The combination with an electric motor having field windings and an accelerating resistor, of dynamic-braking circuits for said motor, means associated with said resistor for controlling the field excitation of said motor during dynamic braking and means including time-limit relays operable after the lapse of a predetermined interval of time and a manual controller for controlling dynamic braking in accordance with the operation of the time-limit relays and in accordance with the electrical connections set up by the manual controller.
8. The combination with an electric motor having a field-magnet winding, a variable resistor disposed to be connected in series circuit relation with said winding, a dynamic-braking circuit cooperating with said motor for producing a dynamic braking effect in the motor, a variable resistor disposed to be connected in series circuit relation with said dynamic-braking circuit, and means for simultaneously varying the resistance values of said variable resistors.
- 60 9. The combination of an electric motor having a field-magnet winding, a variable impedance, a dynamic-braking circuit including the variable impedance and the field magnet winding, means for decreasing the impedance during dynamic braking, means for interrupting the dynamic-braking circuit

through said variable impedance, and means for establishing another dynamic-braking circuit, having a lower impedance than the lowest impedance value of said variable impedance before the circuit through the variable impedance of the first dynamic-braking circuit is interrupted.

10. The combination with an electric motor and dynamic-braking circuits for the motor, means for varying the resistance value of said circuits, time-limit means operable at predetermined intervals of time after the initiation of the dynamic braking operation for increasing the field excitation during dynamic braking to increase the dynamic braking effect and means controlled by said time limit means for further increasing the dynamic-braking effect by varying the resistance value of the dynamic-braking circuit.

11. The combination of an electric motor, a motor field winding circuit the resistance value of which may be varied in predetermined steps over a predetermined range, a dynamic-braking circuit the resistance value of which may be varied in predetermined steps over a predetermined range and means for simultaneously and step-by-step varying the respective resistance values of the field winding circuit and the dynamic-braking circuit.

12. The combination of an electric motor, a motor field winding circuit the resistance value of which may be varied in predetermined steps over a predetermined range, a dynamic braking circuit the resistance value of which may be varied in predetermined steps over a predetermined range, resistance varying means for simultaneously and step-by-step varying the respective resistance values of the field winding circuit and dynamic braking circuit, an auxiliary dynamic-braking circuit having a resistance value lower than the resistance value of the first named dynamic-braking circuit, and means for connecting the auxiliary dynamic-braking circuit to said motor at any selected time during the operation of said resistance varying means.

13. The combination of an electric motor having a field winding and a dynamic braking circuit the respective resistance values of which may be varied, means to initiate the dynamic braking operation, time-limit means operable at predetermined time intervals after the initiation of the dynamic braking operation for proportionally varying the resistance values of the field winding and dynamic-braking circuit, respectively, and means for disproportionately varying the resistance value of the dynamic braking circuit.

14. In a control system for an electric motor, in combination, a motor, a field winding for the motor, a dynamic-braking circuit, including the field winding, disposed to be connected to cooperate with the motor to pro-

duce a dynamic-braking effect in the motor, and means for gradually and proportionally decreasing the ohmic resistance in the dynamic-braking circuit whereby the excitation in the field winding increases during dynamic braking.

15. The combination with an electric motor having a field winding, a variable resistor disposed to be connected in series circuit relation with said winding, a dynamic-braking circuit cooperating with said motor for producing a dynamic braking effect in the motor, a variable resistor disposed to be connected in series circuit relation with said dynamic-braking circuit, and means operable on both of said variable resistors for simultaneously varying the resistance values of said variable resistors in the same direction.
16. The combination of an electric motor, 20 a motor field winding circuit the resistance value of which may be varied in predeter-

mined steps over a predetermined range, a dynamic-braking circuit the resistance value of which may be varied in predetermined steps over a predetermined range, and means for simultaneously and step-by-step decreasing the respective resistance values of the field winding circuit and the dynamic-braking circuit.

17. The combination with an electric motor, manual control means for selectively connecting the motor either as a series motor or as a shunt motor, means for shunting the motor armature during initial stages of series operation, a starting resistor, a plurality of contactors for shunting sections of the starting resistor and time-limit relays for controlling these contactors.

In testimony whereof, I have hereunto subscribed my name this 15th day of May 1930.

WILLARD G. COOK.
